PNEUMATIC DISPATCH TUBE APPARATUS

John T. Needham, North Plainfield, N. J., assignor, by mesne assignments, to Pneumatic Tube Supply Co. of Delaware

Application March 25, 1930, Serial No. 438,809
Renewed March 8, 1932

20 Claims. (Cl. 243—19)

This invention relates to an improved terminal device for a pneumatic dispatch tube system. Important objects of the invention are, to provide an improved terminal head embodying a dispatch tube terminal for discharging carriers, a dispatch tube terminal for sending carriers and a more simple and direct air connection between said terminals for conducting air from the discharge terminal to the sending terminal for the propulsion of a carrier inserted into the latter; to effect said air connection between the terminals through a chamber which also serves as a temporary receptacle for carriers delivered through the discharge terminal; to provide an improved, compact terminal head designed for convenient mounting and operation thereof and embodying a discharge terminal, a sending terminal and an additional terminal for conveniently relaying carriers to another station, and to provide other improved features of design which will appear hereinafter.

In the drawings:

Fig. 1 is a vertical fore-and-aft sectional view of the terminal head, taken on the line 1—1 of Fig. 4;

Fig. 2 a similar section taken on the line 2—2 of Fig. 5;

Fig. 3 a detail section taken on the line 3—3 of Fig. 1;

Fig. 4 a horizontal section taken on the line 4—4 of Fig. 1;

Fig. 5 a front view of the terminal head;

Fig. 6 a detail vertical section taken on the line 6—6 of Fig. 4;

Fig. 7 a detail vertical section taken on the line 7—7 of Fig. 5;

Fig. 8 a detail section taken on the line 8—8 of Fig. 7; and

Fig. 9 a diagrammatic view showing the terminal head connected into a dispatch tube system.

The terminal head forms a unit and its structure includes a casing 1 which forms a temporary receptacle for carriers as they are delivered from a dispatch tube. The casing is a metal casting, substantially rectangular in plan, elongated fore and aft, and having a flat bottom wall 2, flat side walls 3 and an arched wall 4 forming the top and ends of the casing, and serving as a deflector for carriers discharged into the casing from the dispatch tube. Within the casing, near one of the rear corners thereof, the bottom 2 is integrally formed with a nozzle 5 extending upwardly a material distance and open and flared at its upper end. This nozzle forms a discharge terminal for a dispatch tube 6 connected to it. In

one of the front corners of the casing, diagonally opposite the terminal 5, the bottom 2 of the casing is integrally formed with a vertical open nozzle 7 of material height. Nozzle 7 serves as a sending terminal into which carriers are inserted for transmission through a dispatch tube 8 connected to the nozzle. Above the nozzle 7 the wall 4 is formed with a doorway 9 of material size directed forwardly and upwardly. This doorway gives access to the interior of the casing for the removal of carriers discharged from the terminal 5 and for the insertion of carriers into the terminal 7. A hinged door 10 normally closes the doorway.

Overlying the bottom 2 of the casing 1 is a flat carrier supporting plate or platform 11. The latter is hinged as at 12, just forwardly of terminal 5 and substantially midway the height thereof, to a shelf or step 13 at the rear of the casing and formed integrally with it. From its hinge connection the platform extends forwardly to almost the front of the casing. Its width is nearly equal to that of the interior of the casing and, at one of its front corners, it is cut away to clear the terminal 7. A yieldable support 14 located near the forward end of the platform normally holds it horizontal or substantially so. Said support comprises a threaded plug 15 which is screwed into a threaded aperture in the bottom of the casing and is formed at its upper end with a wrench-engaging head 16. A plunger pin 17 is fitted to slide vertically within a bore in said plug and is normally projected upwardly by a spring 18 disposed in the lower end of the bore. At its upper end the pin engages the under side of the platform to yieldably support it. By turning the plug 15 the yieldable support may be vertically adjusted. A check nut 19 is threaded upon the plug to bear against the bottom of the casing and maintain the adjustments.

Beneath the platform 10 and just to the rear of terminal 7 is an electric switch 20. Switch 20 comprises a pair of spring contact fingers 21 and 22 supported upon the bottom of the casing by an insulation block 23 and normally out of contact with each other. The switch forms part of a circuit for a signal lamp 24 mounted upon a bracket 25 at the front of the casing. Upon the under side of the platform is an insulation block 26 which, when the platform is depressed by the weight of one or more carriers thereon, engages the upper contact finger 21 and forces it into engagement with the lower finger 22 to close the lamp circuit. The yieldable support 14 permits the depression of the platform and elevates it to normal position when the weight is removed. The

switch then automatically opens the lamp circuit. A switch 27 to control the circuit of an electrically driven means, not shown, for causing a forced flow of air through the tube system, is 5 also mounted beneath the platform. This switch comprises a pair of normally separated spring fingers 28 and 29 supported at one end upon an insulation block 30 mounted upon the bottom of the casing. A switch operating arm 31 extends 10 fore-and-aft along side the contact finger 29 and is pivoted at its rear end upon a bracket 32 mounted upon the casing bottom. This arm is mounted to swing laterally and is provided at its forward end with an upwardly tapering cam nose 33 15 which projects transversely into terminal 7 through a side slot in the latter. When a carrier is inserted into the terminal it engages the cam nose, forces the arm 31 outward and presses an insulating block carried thereby against the 20 switch finger 29 to close the switch and thereby cause a flow of air through the system, to propel the carrier.

At one side of casing 1 is a sending terminal comprising a tubular casing 34 in the form of a 25 substantially semi-circular loop, disposed in a fore-and-aft plane. A tube 35 is connected to the rear end of said terminal loop, and a tube 36 is connected to the forward end thereof. Above the connection of the latter tube the casing 34 is 30 formed with a forwardly and downwardly directed doorway 37 through which carriers are inserted for transmission through the tube 36. This doorway is conveniently disposed beside the doorway 9 and is normally closed by a hinged door 38.

35 At the front of the terminal head the casings 1 and 34 are covered by a face plate 39 which is removably secured to said casings by screws 40. The plate is rectangular in front view and its lower portion is vertical and extends materially 40 below the level of the bottom of casing 1. Its upper portion recedes to follow the recession of the curved walls of the terminal casings. Along its upper and side edges the plate extends forwardly to form a hood 39'. Within said hood the 45 plate is formed with two apertures 41 and 42 which register with the doorways 11 and 37 respectively of the terminal casings and are of a size and shape to provide clearance for the doors 11 and 38 and their mountings, to be described 50 hereinafter. The lower vertical portion of the face plate carries a plurality of carrier supporting barrels 43 which form a carrier magazine. They extend rearwardly from the plate and open forwardly through it. A cover 44 for the signal 55 lamp 24 is mounted upon the front face of the plate 39. This cover comprises a plate which is removably fastened to plate 39 by screws 45 and centrally formed with an outwardly bulged portion 46 which covers the lamp and is perforated 60 to admit the light through it.

The casing 1 carries a flat frame 47 surrounding the doorway 9 and forming a seat or abutment for the door 10, the latter having an inner facing 48 of suitable soft material to bear against 65 the frame. At its inner side edge the door is hinged as at 49 by means of a pintle sleeve and pintle carried by the door, and a pair of pintle bearings carried by casing 1. Near its opposite edge the door is provided with a rotatable knob 50 to which is fixed a latch 51. The latter is adapted to engage in a notched keeper 52 carried by the casing 1 and projecting forwardly through the aperture 41 in the face plate. Similarly, the terminal casing 34 carries a flat 70 doorway frame 53, pintle sleeves 54 at the inner 75

side edge of doorway 38 and a notched keeper 55 at the outer side edge thereof, projecting through the aperture 42 in the face plate. The door 38 is similarly provided with a compressible inner facing 56, a rotatable knob 57 and a latch 58 operated by the knob and adapted to engage the keeper 55.

80 Mounted upon the terminal casing 34, to the rear of the hinge of the door 38, is a switch casing 59 within which is supported a switch 60. This switch controls a circuit of the electrically driven means and when closed it causes a forced flow of air from tube 35 through the terminal casing to the tube 36 for the propulsion of a carrier through the latter. Switch 60 comprises 85 two normally separated spring contact fingers 61 and 62. The pintle sleeve of door 38 is formed with a cam face 63 which, when the door is opened for the insertion of a carrier, is adapted to force the contact finger 61 against finger 62 and close the circuit.

90 My improved terminal head will operate satisfactorily under either pressure or vacuum in the tube system. An incoming carrier is delivered by the tube 6, through the constantly open terminal 5 and into the casing 1 where it falls upon the platform 11. Its weight then depresses the platform, closes the switch 20 and causes the signal lamp 24 to be illuminated, thereby indicating to an operator the presence of a carrier 95 in the casing. Air which has propelled the carrier into the casing flows through the latter and out through the constantly open terminal 7. The receiving chamber formed by the casing will accommodate a number of carriers and, if desired, the yieldable platform support 14 may be 100 adjusted to yield only when a certain number of carriers are upon the platform. Then, when the signal lamp illuminates the operator knows that it is time to unload the casing by opening 105 the door 10 and removing the carriers. To prevent the delivery of a carrier across the receiving chamber and out through the terminal 7 the door is provided with a stop rib 64 which, when the door is closed projects across the terminal and 110 obstructs its entrance. When the door is opened this obstruction is removed and the terminal is readily accessible just within the doorway for the insertion of a carrier to be dispatched. Insertion of the carrier closes the switch 27 and 115 starts a flow of air from the terminal 5 across the interior of the casing and into the terminal 7 for the propulsion of the carrier. By forming an air connection between the discharge terminal and the sending terminal directly through the 120 carrier receiving chamber I materially simplify 125 the air circulation.

130 The complete terminal head forms a compact unit which is designed for convenient mounting upon a desk or within a compartment of a desk. 135 The mounting of the three terminals closely adjacent to each other is particularly convenient. In some dispatch tube systems a station may have no direct delivery connection with the central station and must rely upon an intermediate 140 station to relay carriers to it. Such a system is diagrammatically illustrated in Fig. 9. Carriers arriving in casing 1 at station S for relay are inserted into the terminal 7 therein and dispatched through the tube 8 to the station S'. The latter is connected to the central station C through the tube 35, the terminal casing 34 and the tube 36, but has no connection for receiving carriers directly from the central station. The carriers which are addressed to station S and 145

150

not intended for relay are removed from the casing 1, while carriers are dispatched directly to the central station from station S by inserting them into casing 34. The terminal head 5 may, however, be used in other systems with different tube connections. The terminal 7 for example may be directly connected to the central station instead of to the outlying station S'.

While I have shown and described a very satisfactory form of my invention I do not wish to be limited strictly to this disclosure but reserve the right to make such changes as will lie within the scope of the claims.

What I claim is:

1. In a pneumatic dispatch tube apparatus, a unitary terminal device comprising a casing forming a chamber to receive a number of carriers; a dispatch tube discharge terminal opening into said chamber for the delivery of carriers to the 20 chamber; a dispatch tube sending terminal opening into the chamber; a support for the delivered carriers within the casing adapted to be depressed by the weight of the carriers; signal means adapted to be operated by depression of said support 25 to indicate the presence of carriers in the casing; electric circuit-closing means adapted to be operated by the insertion of a carrier into said sending terminal to close a circuit for causing a forced circulation of air through the apparatus, the said 30 terminals being constantly open within said chamber and the carrier receiving space of the chamber forming a passage for the direct flow of air from the discharge terminal to the sending terminal; a door giving access to the chamber 35 and closing a doorway through which carriers may be passed; and an additional sending terminal connected to the casing.

2. In a pneumatic dispatch tube apparatus, a unitary terminal device comprising a casing forming a carrier receiving chamber; a dispatch tube discharge terminal opening into said chamber for the delivery of carriers thereto; a dispatch tube sending terminal opening into the chamber, the 45 chamber forming a passage for a flow of air from said discharge terminal to the sending terminal for the propulsion of a carrier inserted into the latter; and an additional sending terminal attached to the casing.

3. In a pneumatic dispatch tube apparatus, a unitary terminal device comprising a dispatch tube discharge terminal having a dispatch tube connection with a central station; a dispatch tube sending terminal having a dispatch tube connection with an outlying station; and a casing 55 into which both of said terminals open forming a passage for the flow of air between said terminals for the transmission of carriers received in the apparatus, said casing having a door giving access to the interior of the casing and closing a doorway through which carriers may be passed; and a sending terminal attached to said casing, having an entrance closely adjacent to said casing door for the insertion of carriers and having dispatch tube connections with the sending terminal of said outlying station and the discharge 65 terminal of the central station.

4. In a pneumatic dispatch tube apparatus, a terminal device comprising a casing forming a carrier receiving chamber; a dispatch tube discharge terminal having a dispatch tube connection with a central station and opening into said chamber for the delivery of carriers thereto from the central station; a dispatch tube sending terminal opening into the chamber and having a dispatch tube relay connection with an outlying

station for transmitting carriers to said outlying station, the chamber forming a passage for a flow of air from said discharge terminal to the sending terminal; and a second sending terminal mounted closely adjacent to said casing and having a dispatch tube connection with the sending terminal of said outlying station and a dispatch tube connection with the discharge terminal of the central station.

5. In a pneumatic dispatch tube apparatus, a casing forming a carrier receiving chamber; a dispatch tube discharge terminal opening into said chamber for the delivery of carriers to the chamber; a platform mounted within the chamber to support the delivered carriers and depressible by the weight of the carriers thereon; a yieldable support for the platform to normally hold it elevated and yieldably resist depression thereof; and means rendering said platform support vertically adjustable.

6. In a pneumatic dispatch tube apparatus, a casing forming a carrier receiving chamber; a dispatch tube discharge terminal opening into said chamber for the delivery of carriers to the chamber; a dispatch tube sending terminal opening into the chamber; a door giving access to the chamber and closing a doorway through which carriers may be passed; a second sending terminal disposed adjacent said casing; a door to give access to said latter terminal disposed closely adjacent to said door of the casing; a front structure framing said two doors; and a plurality of carrier holders carried by said front framing structure.

7. A pneumatic dispatch tube terminal device comprising a casing forming a carrier receiving chamber; a dispatch tube discharge terminal opening into said chamber for the delivery of carriers to the chamber; a dispatch tube sending terminal opening into the casing; a door affording access to the chamber and closing a doorway through which carriers may be passed; a second sending terminal disposed adjacent said chamber and having an entrance located closely adjacent to said door of the casing; and a front structure framing said door and said terminal entrance.

8. A pneumatic dispatch tube terminal device comprising a unit formed for fitting into a forwardly opening compartment of a desk or similar article of furniture and comprising a casing forming a carrier receiving chamber; a dispatch tube discharge terminal opening into said chamber for the delivery of carriers into the chamber, the casing having a forwardly directed entrance affording access to the chamber for the removal of carriers therefrom; a sending terminal disposed adjacent said chamber and having a forwardly directed entrance located closely adjacent to said casing entrance; and a front structure framing said two entrances and formed to close the furniture compartment.

9. A pneumatic dispatch tube terminal device comprising a casing forming a carrier receiving chamber; a dispatch tube discharge terminal opening into said chamber for the delivery of carriers thereto; a dispatch tube sending terminal opening into the casing, the casing having a door affording access to its interior and closing a doorway through which carriers may be passed; and an additional sending terminal having an entrance located closely adjacent to said door.

10. A pneumatic dispatch tube terminal device comprising a unit formed for fitting into a forwardly opening compartment of a desk or similar article of furniture and comprising a casing forming a carrier receiving chamber; a dispatch

- tube discharge terminal opening into said chamber for the delivery of carriers thereto; a dispatch tube sending terminal opening into the casing, the casing having an entrance at its front facing forward and upward and affording access to the chamber and through which carriers may be passed; another sending terminal disposed adjacent the first and having a forwardly and upwardly directed entrance adjacent said casing entrance; rearwardly inclined doors closing said entrances; and a front structure formed to close the front of the furniture compartment and having a rearwardly inclined front wall portion framing said doors and a forwardly opening cowl portion extending forward over the doors. 80
- 5 11. A pneumatic dispatch tube terminal device comprising a unit formed for fitting into a forwardly opening compartment of a desk or similar article of furniture and comprising a dispatch tube sending terminal for disposal in said compartment and having a forwardly and upwardly directed entrance; a rearwardly inclined door for said entrance; and a front structure formed to close said compartment and having a rearwardly inclined front wall portion framing said door, and a forwardly opening cowl portion extending forward over the door. 85
- 10 12. A pneumatic dispatch tube terminal device comprising a unit formed for fitting into a forwardly opening compartment of a desk or similar article of furniture and comprising a dispatch tube sending terminal for disposal in said compartment and having a forwardly and upwardly directed entrance; a rearwardly inclined door for said entrance; and a front structure formed to close said compartment and having a rearwardly inclined front wall portion framing said door, a forwardly opening cowl portion extending forward over the door, and a front wall portion depending below the door; and a plurality of forwardly opening, tubular carrier holders carried by said depending wall portion and extending rearward therefrom. 90
- 15 13. A pneumatic dispatch tube terminal device comprising a casing forming a carrier receiving chamber; a dispatch tube discharge terminal opening into said chamber for the delivery of carriers thereto; a hinged, depressible platform mounted within the chamber to receive the delivered carriers thereon; a signal circuit-closing means operable by depression of the platform under the weight of the carriers for operating a signal; a dispatch tube sending terminal opening upward into the chamber and extending above the bottom thereof; electric air control circuit closing means, comprising a pair of normally separated contact members mounted between the bottom wall of said chamber and the platform and covered by the latter, one of said contact members being laterally shiftable toward and from the other and having a cam nose projecting laterally into the sending terminal through an aperture in the side of the terminal and engageable by an inserted carrier for closing a circuit to start a flow of carrier propelling air through the terminal, the contact members and their connections being accessible by raising the hinged platform. 100
- 20 14. A pneumatic dispatch tube terminal device comprising a unit for fitting into a forwardly opening compartment of a desk or similar article of furniture and including a casing forming a carrier receiving chamber; a dispatch tube discharge terminal opening into said chamber for the delivery of carriers into the chamber; a dispatch
- 25 tube sending terminal opening into the casing, the casing having an entrance at its front facing forward and affording access to the interior of the casing and formed to permit carriers to be passed through it; another sending terminal disposed adjacent the first sending terminal and having a forwardly facing entrance; and a front structure framing said two entrances and formed to close the front of the furniture compartment. 105
- 30 15. A pneumatic dispatch tube terminal device comprising a casing forming a carrier receiving chamber; a dispatch tube discharge terminal opening into said chamber to deliver carriers into the chamber; a substantially U-shaped dispatch tube loop connected to said casing and having a connection for an incoming dispatch tube at one end, a connection at its other end for an outgoing dispatch tube and an opening at an intermediate point in the loop for insertion of carriers for transmission through said outgoing tube. 110
- 35 16. A pneumatic dispatch tube terminal device comprising a casing forming a carrier receiving chamber and having an arched top; a dispatch tube discharge terminal opening into said chamber to deliver carriers into it; a dispatch tube loop disposed alongside said casing, of approximately inverted U form and having a curvature conforming approximately to the arch of the casing top, said loop having a connection at one end for an incoming dispatch tube, a connection at its opposite end for an outgoing dispatch tube and an opening at an intermediate point for insertion of carriers for transmission through said outgoing tube. 115
- 40 17. A pneumatic dispatch tube terminal device for fitting into a forwardly opening compartment of a desk or similar article of furniture and including a casing forming a carrier receiving chamber; a dispatch tube discharge terminal opening into said chamber for delivery of carriers into the chamber; a dispatch tube sending terminal opening into the casing, the casing having an entrance opening at its front facing forward and affording access to the interior of the casing and formed to permit carriers to be passed through it; an approximately U-shaped dispatch tube loop disposed alongside said casing and connected thereto and having a connection at one end for an incoming dispatch tube, a connection at its opposite end for an outgoing dispatch tube and a forwardly facing entrance opening at an intermediate point in the loop for insertion of carriers for transmission through the said outgoing tube; and a front wall structure framing said entrance openings of the casing and loop and formed to close the front of the furniture compartment. 120
- 45 18. A pneumatic dispatch tube terminal device comprising a casing forming a carrier receiving chamber; a dispatch tube discharge terminal opening into said chamber for the delivery of carriers thereto; a depressible platform mounted within the chamber to receive the delivered carriers thereon; a signal circuit-closing means operable by depression of the platform under the weight of the carriers for operating a signal; a dispatch tube sending terminal opening upward into the chamber, the casing having an entrance opening formed to permit carriers to be passed through it; and electric air control circuit-closing means disposed beneath said platform and operable by insertion of a carrier into said sending terminal to close a circuit to start a carrier propelling flow of air through the sending terminal. 125
- 50 75

nal, the platform being upwardly shiftable to afford access to said two circuit-closing means.

19. A pneumatic dispatch tube terminal device comprising a carrier receptacle; a dispatch tube discharge terminal directed into said receptacle for delivery of carriers thereto; a depressibly mounted platform disposed within the receptacle to receive and support the delivered carriers thereon; and signal circuit-closing means beneath the platform and operable by depression of the platform under the carrier weight to close a signal circuit, said platform being shiftable upward to afford access to said circuit-closing means.

15

20. A pneumatic dispatch tube terminal device comprising a carrier receptacle; a dispatch tube discharge terminal opening into said receptacle for delivery of carriers thereto; a hingedly mounted depressible platform within the receptacle to receive and support the carriers thereon; and signal circuit-closing means beneath the platform and operable by depression of the platform under the carrier weight to close a signal circuit, said platform being shiftable upward about its hinge to afford access to said circuit-closing means.
